UNITED STATES PATENT OFFICE.

ARTHUR L. PERRINE, OF CLEVELAND HEIGHTS, OHIO.

SPIRIT LEVEL.

Application filed June 7, 1924. Serial No. 718,648.

To all whom it may concern:

Be it known that I, ARTHUR L. PERRINE, a citizen of the United States, residing at Cleveland Heights, in the county of Cuyahoga and State of Ohio, have invented a certain new and useful Improvement in a Spirit Level, of which the following is a full, clear, and exact description, reference being had to the accompanying drawings.

10 This invention relates to spirit levels, such as used in building construction. The essential object is to provide for illuminating the level tubes of such instruments with suitable electric lamps. Another object is 15 to provide a compact lighting system for a spirit level which will not detract from the appearance of the article. Further objects include the provision of a cheaply manufactured illuminated spirit level wherein 20 standard electric fixtures such for instance as are used in flash lights may be used advantageously, with a minimum amount of change in the standard construction of the level itself.

25 Other features and objects of my invention will become apparent in the further description of my invention which pertains to the accompanying drawings. The essential characteristics thereof will be defined and 30 summarized in the claims.

In the drawings Fig. 1 is a side elevation of my illuminated spirit level; Fig. 2 is a perspective showing the adaptation for connecting the battery to the lighting system 35 and securing it in the level; Fig. 3 is a transverse section through the battery socket as indicated by the lines 3—3 on Fig. 1; Fig. 4 is a similar sectional view showing battery terminal clips, as indicated by the line 40 4—4 on Fig. 1; Fig. 5 is a wiring diagram; Fig. 6 is a fragmentary plan of one of the illuminated tube units, and the electric switch, portions of the cover plate being broken away to disclose these parts; Fig. 7 45 is a transverse cross section as indicated by the line 7—7 on Fig. 6 showing the bulb supporting means; Fig. 8 is a similar cross section as indicated by the line 8—8 on Fig. 6 showing the switch; Fig. 9 is a transverse 50 cross section as indicated by the line 9—9 on Fig. 1.

I propose to position the battery in one end of the level in such a manner that the insertion of the battery into the aperture provided for it will establish the desired electric connection. The preferred method of

providing for a wire conduit in a metal level consists of utilizing the usual marginal stiffening webs, one of which will be grooved and adequately covered and which will communicate with covered recesses surrounding the spirit tube units for containing the lamp and with the desired switches.

In the drawings 1 indicates the usual rectangular frame of a level the sides 5 and 6 as well as the end faces 7 being formed as near as possible into a perfect plane. Horizontal spirit tubes 8 and 9 each containing fluid and an air space or bubble 10, are shown as supported in cylindrical holders 11. The axes of each pair of tubes describe opposed, that is to say convex curves. The purpose of this arrangement is to provide for more quickly ascertaining the approximate level of the plane surface nearest the tube. For instance, when the surface 6 of the level frame rests upon the surface of a building member to be leveled the operator watches the lower of the tube 8, since the bubble therein more quickly finds the central region of the tube. The use of the vertically placed tubes 15 and 16 is substantially the same, except that these are used for vertical leveling, that is to say in place of a plumb line. In this use whichever of the tubes happens to be uppermost as the operator picks up the level will give the desired reading.

For the above reasons I find it most desirable to illuminate all of the spirit tubes as near the center of the convex side of each of the tubes as possible. Accordingly I show a lamp 20 partly within the holder 11 and between the pair of horizontal tubes. Each of the vertical leveling tubes are illuminated by light bulbs 22 and 23, so placed that in use the bulbs will be nearest the surface of the tube along which the bubble travels.

I have arranged for positioning an electric battery B within a receptacle 25 formed in one end of the level frame. A closed portion 26 of the frame forms the bottom of the receptacle, and a transverse partition 22 the inner end thereof. The side and end wall portions of the level frame completes the receptacle. Spring clips 27 and 28 upon the floor of the receptacle are spaced apart therefrom by suitable insulating strips and washers 29 and 30. The spring terminals b and b' engage the spring clips when the battery is lowered into the receptacle.

The battery and terminals are held in place by a cover plate 31 which fits a groove 32 in the frame and may be held in place by a tongue 33 on the plate and a screw 34. The wall 22 is slotted at 35 for admitting the terminal wires, and the bottom portion of the slot reaches substantially the depth of a groove 36 along the web 37 of the frame. This groove extends practically the entire

- 10 length of the web and has shoulders at 38 and 39 for better receiving and supporting a cover plate 40. Adjacent the groove and surrounding the level tubes are provided receptacles substantially similar to that 15 shown in Fig. 6 and which are formed by the side walls 41 and 42, the webs and a floor or rear wall portion 43.

A convenient form of supporting the spirit tubes consists of a cylindrical barrel 45 carried

- 20 between the ribs 37 and 38 and supported thereby, which barrel carries a shorter inner barrel designated 46. This latter barrel may support at its ends transparent plates as indicated at 47 in Fig. 1, 25 for protecting the spirit tube. I prefer to provide apertures as indicated at 50 and 51 in both these barrels and slightly back of the apertures I provide a socket 52 for receiving a small electric light bulb. This socket 30 may comprise a tubular strip of metal as shown in Fig. 7 at 53 having suitable screw threads formed therein for receiving the shank of the bulb and having a looped attached portion 54. The loop receives the 35 end of a conductor wire which is clamped therein by a screw 55. The return circuit from the lamp may be established by another spring clip 57 having a terminal loop and attaching screw similar to that of the 40 socket.

As shown in Fig. 5, the lead 60 from the battery B terminates in a switch 61. A lead 56 from this switch returns to the buss wire 58, to which the lamps 20, 22 and 23 are 45 connected in parallel, the circuit being completed by the buss wire 66.

The switch as shown in Figs. 6 and 7 preferably consists of a pair of leaf spring members 65 and 66 secured to the floor 43. 50 The upper leaf carries a button 67 which projects through a dished region of the cover plate 68. In this position the control switch does not detract from the otherwise balanced appearance of the level and is in 55 the most likely place where the fingers of the operator would grasp the instrument, when applying it to his work.

The cover plates for all the units are substantially alike and are secured along one 60 edge to the web 37 by one or more screws 72 while the other edge is bent to lie beneath the edge of the strip 40. Suitable screws 70 may hold the strip in place which 65 may engage bosses 71 adjacent one corner of each receptacle as shown. The end of

the frame unoccupied by a battery may be closed as at 75 to give the level a symmetrical and balanced appearance.

It will be seen that I have provided an illuminated level construction which may be 70 easily adapted to levels now in use and which will not detract from the appearance thereof. It will be seen further that I have fitted the component parts of the lighting circuit into receptacles forming 75 part of the frame construction in such a manner as to afford the most ample protection against accidental damage. The lamps are most advantageously located with respect to the level tubes and are so concealed by the tube holding frames that the operators' eyes will be shielded from the direct glare from the filament.

Having thus described my invention, I 80 claim:

1. In combination with a metal lever frame substantially I shaped in cross section, a tubular member carried by the web of the I, a spirit level tube positioned 90 across said tubular member having an opening in the side wall thereof, a cover plate forming with the flanges of the web a compartment surrounding the tubular member, said plate having an opening fitting over the tubular member whereby the tubular 95 member is opened to sight at either side of the frame, a light bulb mounted in the compartment adjacent the opening in the tubular member, and means for supplying power to the bulb.

2. In a level, a frame substantially I shaped in cross section, a cylindrical hollow boss having an opening in the side thereof and carried by the web of the I, a spirit level positioned across the boss, ribs 105 extending transversely of the frame and rising from the web at either side of the boss, a cover extending on either side of the flanges on one side of the I and resting on the ribs to form with the web a substantially closed compartment, said cover having an opening registering with the boss and a light bulb carried in the compartment 110 adapted to illuminate the level through the opening in the boss.

3. A level having a frame substantially I shaped in cross section, ribs rising from the webs of the I, and a plate resting thereon and secured to the frame to form with the web and ribs a compartment, a tubular member also carried by the web and registering with an opening in the plate, said tubular member having an opening in the wall thereof leading into the compartment, a spirit level carried by the tubular member, 125 a light bulb secured to the frame within the compartment and adjacent the opening in the tubular member to illuminate the level and means carried by the level frame to supply power to the light.

4. In combination with a metal level frame, said frame having a web and flanges extending transversely thereof, means associated with the web for supporting a spirit level tube and a compartment adjacent the tube supporting means comprising the web and flanges and a cover plate extending between the flanges, a light bulb mounted in the compartment and arranged to illuminate the tube, a groove for a conductor wire adjacent one of the flanges and communicat-
- ing with the compartment, a battery carried in a separate compartment, said latter compartment also communicating with the groove, a cover plate for the groove, said cover plates being in overlapped relation whereby the outer one serves to hold the inner in place. 15

In testimony whereof, I hereunto affix my signature.

ARTHUR L. PERRINE.
